BRAKE-OPERATING MECHANISM.

1,373,194.

Specification of Letters Patent. Patented Mar. 29, 1921.

Application filed March 10, 1919. Serial No. 281,808.

To all whom it may concern:

Be it known that I, EZRA B. MEAD, a citizen of the United States, residing in Ottumwa, in the county of Wapello and 5 State of Iowa, have invented a new and useful Improvement in Brake-Operating Mechanism, of which the following is a specification.

This invention relates in general to 10 trols for brakes for mine hoists and other apparatus and although the invention is hereinafter shown and described in connection with a mine hoist control of the character disclosed in my co-pending applica- 15 tion Serial No. 851,891 it will be readily understood that it may with equal value be used in other connections.

The invention contemplates the use of oil or other incompressible liquid supplied under pressure to control the operation of the 20 brake, and with the resulting advantages of such a control medium the provision also of the advantages that ordinarily only attend the use of a compressible medium such 25 as air, and this without the presence of the disadvantages heretofore believed inherent when either of these mediums have been employed. The air being highly compressible and elastic has not provided a control of 30 sufficient stability in apparatuses of the character of mine hoists so that when the brakes were moved the brake weight had a marked tendency to bounce. The use of oil or like liquid provides a positive and quick 35 operating control, but is highly sensitive and to prevent too sudden stopping and starting of the cage requires close attention to the careful manipulation of the brake control valve. It is a principal purpose of 40 my invention to provide against this sudden starting and stopping under normal action of the cage in a control using an incompressible liquid as oil to the end that the positive action may still be preserved and this 45 action instead of being instantaneous shall be spread out over a small period of time, so that the starting and stopping must automatically be smooth and without abrupt jar.

My invention contemplates to this end the 50 utilization of a force controlled by the pressure of the oil itself for delaying or spreading the application of the full pressure over a small or even a minute period of time. The means or agency I prefer to employ 55 for this purpose is an air pocket appropri-

ately located to be compressed by the oil or other liquid used when the full pressure is open to the cylinder and to retard as the air expands the full release of this pressure. It might be well to mention that 60 usually in the past particular care has been taken to provide against the opportunity for the existence of air pockets in systems of this character.

A further and highly important object of 65 the invention is the provision of a brake control for mine hoists, that will attain these desirable results without increasing the complexity of the apparatus, without increasing materially its cost and without 70 incorporating in it any sensitive or delicate part that may require frequent repair or replacement or otherwise affect the durable and efficient character of the apparatus.

Numerous other objects and advantages 75 of the invention will be apparent from the following description when taken in connection with the accompanying drawing illustrating a preferred embodiment thereof.

On the drawing,

Figure 1 is a diagrammatic view of a 80 brake control in which my present invention is embodied; and

Fig. 2 is an enlarged vertical section through the air cushion providing drum or 85 dome.

For the purpose of illustrating my present invention, I have shown on the drawing a sample layout of a brake control. Reference character 11 indicates a sump or drain 90 reservoir from which the oil is delivered by pump 12 to an accumulator or pressure reservoir 13, through pipes 14 and 15. A pipe connection through pipes 15, 16 and 17, valve 18, pipe 19, air drum 21, pipe 22, 95 valve 23, pipes 24, 25 and 26, connects the pressure reservoir or accumulator 13 with a brake cylinder 27, adapted in any suitable or preferred manner to control the action of the brake, by lifting the brake weight 20. 100 It will be understood of course that this weight is connected with the brake in the manner usually employed in hoists of this character. In the present instance the cylinder acts to permit the setting of the 105 brake when the pressure of the oil in it is relieved or withdrawn, that is to say the brake is normally set or applied, and the hoist can only be operated when the communication through the pipe connection just 110

mentioned is open and the pressure is felt in the cylinder in sufficient amount to counteract the positive brake applying means (not shown) with which brakes in mine 5 hoists are usually provided. If, however, either valve 18 or valve 23 be closed the brake is applied as a result. Valve 18 is the valve under the control of the operator and the one utilized in the normal operation of 10 the hoist, and valve 23 is an emergency valve electrically or mechanically controlled to cut off communication through the pipe line under pre-determined conditions rendering it essential that the brake 15 be applied and this without any action by the operator. When either of the valves 23 and 18 is moved to interrupt the communication with the accumulator, it establishes communication with the reservoir 11 and 20 the cylinder 27, the valves 18 and 23 being each three-way valves. The communication established by the valve 18 between the cylinder and the reservoir 11 is through pipes 28, 29 and 31 and that established by 25 the valve 23 is through pipes 32, 29 and 31.

The air drum 21 shown in enlarged section, Fig. 2, provides merely a pocket in which a quantity of air may be contained, and is shaped to provide an enlarged upper chamber 33 and a restricted lower chamber 34. With this lower chamber the two pipes 22 and 19, have free communications, their 30 adjacent ends being threaded into the wall of the dome 21, leakage being prevented by 35 stuffing boxes 35 or otherwise.

The air drum is preferably positioned between the two valves, although of course it might be otherwise located. It is not always, however, desirable to exert a softening 40 or restraining influence upon the action of the hoist resulting from an application of the brake applied by action of the emergency valve 23, for conditions may be such that instant stopping is imperative. The 45 air cushion in the lay-out of the drawing affects only the hoist when controlled by the operator's valve 18. When the communication is first established with the cylinder to release the brake, the air in the 50 chamber 33 is of course compressed under the pressure of the accumulator 13 and a release of this pressure by a manipulation of the valve 18 permits an expansion of the air in the reservoir and during this expansion 55 the pressure producing the compression must be absorbed in the oil before the brake can be completely applied. The time required for this is, of course, minute, but it is sufficient to do away with the too abrupt 60 halting of the cage.

It is thought that the invention and many

of its attendant advantages will be understood from the foregoing without further description, and it will be apparent that various changes may be made in the form, 65 construction and arrangement of the parts of the brake control without departing from the spirit and scope of the invention or sacrificing all of its material advantages, the form hereinbefore described being merely 70 a preferred embodiment thereof.

I claim:

1. In a brake control for mine hoists and the like, an incompressible fluid system including an accumulator, a thrust cylinder, a 75 drain reservoir, and connections between the same including an air cushion and pipe and valve members, said air cushion and valve members being arranged in said connection to include the air cushioning means into direct communication with the thrust cylinder in releasing the brake and providing for its exclusion in applying the brake under certain emergency conditions. 80

2. A brake control for mine hoists and the like, comprising in combination an incompressible fluid system and a thrust cylinder, said system including an accumulator, and a drain reservoir, pipes connecting said accumulator with said thrust cylinder, a valve in 90 said pipe connections, and cushioning means between said valve and said accumulator.

3. In a brake control for mine hoists and the like, the combination of a thrust cylinder for releasing the brake, means acting against 95 pressure in said thrust cylinder for applying the brake, means for supplying oil under pressure to the thrust cylinder to release the brake and deliverable to said thrust cylinder in controlled amount and pressure to 100 produce application of the brakes, and a cushion in said second mentioned means.

4. A brake control for mine hoists and the like, comprising in combination a brake cylinder, a means for supplying an incompressible liquid under pressure to said cylinder, a manually controlled valve in said means for controlling normal operation of the brake, and an emergency valve, and a cushion for influencing the action of the 110 brake cylinder when the manually controlled valve is operated, said cushion being inactive when the emergency valve applies the brake.

5. A brake control for mine hoists and the like, comprising in combination a brake 115 cylinder, a reservoir, a pipe connection between said reservoir and said brake cylinder, two valves in the pipe connection from the reservoir to the cylinder, and an air drum or dome in said pipe connection and 120 between said valves.

EZRA B. MEAD.
